UNITED STATES PATENT OFFICE.

PETER LAMB, OF WINNIPEG, MANITOBA, CANADA.

KNIFE-CLEANER.

1,393,449.

Specification of Letters Patent.

Patented Oct. 11, 1921.

Application filed June 24, 1920. Serial No. 391,389.

To all whom it may concern:

Be it known that I, PETER LAMB, of the city of Winnipeg, in the Province of Manitoba, Canada, have invented certain new and useful Improvements in Knife-Cleaners, of which the following is the specification.

The invention relates to improvements in knife cleaners and the object of the invention is to provide a simply constructed, inexpensive and durable cleaner which can be readily manipulated by the hand and which will act to efficiently clean the knife.

A further object is to provide a cleaner having a renewable cleaning head.

With the above objects in view the invention consists essentially in a handle, a cork head and means for detachably connecting the head to the handle, the parts being arranged and constructed as hereinafter more particularly described, reference being had to the accompanying drawing in which:—

Figure 1 is a side view of the device as it appears when in use.

Fig. 2 is an enlarged side view of the knife cleaner.

Fig. 3 is a plan view.

Fig. 4 is a longitudinal sectional view.

Fig. 5 is a perspective view of a portion of the handle and showing the piercing prong.

In the drawing like characters of reference indicate corresponding parts in the several figures.

1 represents a handle of any convenient form, which handle has the front end squared and provided with an extending piercing prong 2. 3 is a rubbing head such as a cork. In the present instance this is tapered as is usual and the small end of the cork is placed uppermost and the cork is initially attached to the handle by piercing the prong into the cork.

Here it will be observed that the prong is at the lower side of the handle and that the end of the handle forms a shoulder at 4 engaging the side of the cork.

The final fastening of the cork is accomplished by passing a metal band 5 in the form of a clamp around the upper end of the cork and passing a fastening bolt 6 through the handle and ends of the band which projects to the sides of the handle.

When the fastening is completed the cork is very securely attached to the handle although it can be readily removed by undoing the screw, springing the band and withdrawing the cork from the prong. This demountable feature allows of a new cork being easily and quickly attached to the handle when the original one is worn away.

When the knife cleaner is to be used one grasps the handle in the hand with the handle caught between the thumb and second finger and the first finger lying on the top end of the cork. This is the position shown in Fig. 1, and it will be readily apparent that the blade end of the underlying knife 7 can be readily cleaned by rubbing it in the ordinary way with the cork, while utilizing any of the well known cleaning powders. By placing the first finger on top of the cork it is a very easy matter to press down while working the cork backwardly and forwardly over the knife blade.

What I claim as my invention is:—

A device of the character described comprising a handle reduced at one end to provide a sharpened spur at the lower side thereof and a shoulder portion above the spur, a rubbing head impaled on the spur and abutting said shoulder portion and a split clamping band extending around the rubbing head in clamping engagement therewith and having the ends thereof fastened to the sides of the handle.

Signed at Winnipeg, this 30th day of April, 1920.

PETER LAMB.

In the presence of—

JOHN M. BUTH,
MINNIE LAMB.
